UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK

TRANSMISSION BY MODULATED WAVES.

Application filed February 28, 1923. Serial No. 621,710.

This invention relates broadly to signaling and more particularly to multiplex telephony conducted either by line wire or radio.

One of the objects of the invention is to en-

5 able simultaneous transmission of a plurality of signals or control waves on a common carrier wave without interference or cross modulation.

A further object of the invention is to pro-
10 vide for multiplex telephone transmission by means of a single carrier wave modulated by a plurality of signal waves of different frequency ranges without cross-modulation between the various signal waves.

15 Another object of the invention is to provide for multiplex telephone transmission by means of a single carrier wave generator and a number of separate signaling channels without transmission of the carrier wave fre-
20 quency to the receiving station.

Another object is to provide for modulation of carrier waves by signal waves or side bands representing signals to produce new signal-representing side bands and for the
25 suppression of both the carrier waves and the signal waves or side bands used for modulation from the output current.

Another object of the invention is to pro-
30 vide a receiving circuit cooperating with the multiplex transmitting system of this invention whereby the carrier wave frequency is re-
stored at the receiver and the different signals are separated.

A further object of the invention is to pro-
35 vide a circuit arrangement at a transmitter for connecting any number of separate signaling circuits to the modulator circuit whereby separate signaling channels are developed, effectively spaced in frequency by
40 predetermined fixed frequencies supplied in-
dependently to each or each but one of the signaling channels.

A still further object is to provide for the elimination of cross modulation between the
45 side frequencies in the several channels of the transmitter circuit by limiting the waves transmitted to either the upper or lower side bands of the single carrier wave.

Another object of the invention is to pro-
50 vide means at the receiver for passing the side frequencies received to selector circuits, isolating the several signaling frequencies, and receiving the signals on different channels independently one from the other.

Other and further objects of the invention 55 will be understood from the following specification and accompanying drawings in which:

Fig. 1 is a circuit diagram showing the arrangement of transmitting apparatus of a 60 multiplex telephone system and Fig. 2 is a circuit diagram of the receiving circuit em-
ployed.

The invention relates both to the system 65 and method of operation of the multiplex tele-
phone arrangement herein described.

The transmitting system shown in Fig. 1 includes a generator 1 of carrier wave fre-
quency which may be valued for purposes of 70 illustration at 100,000 cycles, represented as frequency C. A balanced electron tube mod-
ulator 2 is used consisting of two electron tubes 3 and 4 oppositely related to the carrier source with reference to grid excitation, that is, the carrier wave is applied to the two tubes 75 in opposite phase. The carrier wave energy is impressed on the modulator by transformer 5 having primary winding 6 and secondary windings 7 and 8. The modulator circuit in-
cludes grid battery 9, a battery A for exciting 80 the filament circuits of tubes 3 and 4 and source B for energizing the plate circuits. The output circuit of the modulator tubes in-
cludes primary windings 10 and 11 of trans-
former 12 having secondary winding 14. 85

The output current of the balanced modu-
lator includes the desired side frequency 90 waves and an unmodulated carrier wave com-
ponent. This unmodulated carrier wave component may be neutralized by an equal 95 amplitude and opposite phase wave of the carrier frequency applied through an ampli-
fier 15 shunting the modulating system in the manner illustrated in Englund Patent No. 1,258,548 dated March 5, 1918, reissued April 19, 1921 as No. 15,089.

The input circuit of amplifier 15 is con-
nected through an autotransformer 16 to the 100 terminals of the generator 1, the purpose of the autotransformer connection being to reg-
ulate the voltage impressed upon the input circuit of the amplifier 15. The output cir-
cuit of the amplifier is connected to a phase 105 regulator 17 of suitable form and the voltage across a section of the network is then applied to the input circuit of power amplifiers 20. This voltage has the same frequency as that produced at the terminals of carrier wave

generator 1 but it is so regulated as to intensity and phase as to exactly neutralize the unmodulated carrier wave component of the output current of the modulator.

In the input circuit of the modulating tubes means are provided, such as transformers 21, 22 and 23, for inductively connecting any number of different voice signaling circuits with the modulator. The 10 windings 21^a, 22^a and 23^a are connected in the input circuit of the modulator while windings 21^b, 22^b and 23^b are connected to each of the signaling circuits respectively. Each of the signaling circuits consists of a 15 microphone 25, transformer 26 and battery 27 related to the input circuit of an electron tube device 28. The device 28 in the first channel serves merely as an amplifier and may be omitted from this channel if amplification of the speech waves is unnecessary. Such a channel for example is that containing the filter F¹ which passes speech frequency currents of from 200-2000 cycles per second. The output from this band filter 20 is then impressed on the grid circuit of the balanced carrier wave modulator as the signal of one channel of the system. A signal applied in this manner may be considered to be applied to the two tubes in the same 25 phase.

In the other channels the device 28^a functions as a modulator and its input circuit is supplied with continuous waves by a source 50 of oscillations which in one channel 30 may be, for example of 2,000 cycles frequency. The voice frequencies are superimposed in the grid circuit together with the current of 2,000 cycle frequency delivered by the generator. The output of the 35 electron tube 28^a, which operates as a modulator, furnishes to a band filter F² one side frequency band which ranges between 2,200 cycles and 4000 cycles. Filter F² is designed to transmit currents within this range to 40 the exclusion of other currents impressed upon it. The band filters employed in the circuits of the present application are of the Campbell type shown in Patents Nos. 1,227,113 and 1,227,114 granted May 22, 1917 45 to George A. Campbell. The output from this band filter is then transferred to the grid circuit of the balanced carrier wave modulator 2 and transmitted as a second signaling channel. It will be noted that the 50 wave filter F₂, transmits a band of waves representing speech but with all frequencies increased by 2000 cycles.

Similarly another speech signal increased in frequency by energy supplied from a generator of 4000 cycles developing a side frequency between 4200 and 6000 cycles is also supplied to the grids of the balanced carrier wave modulator 2. This signaling circuit includes a band filter F³ which eliminates 55 all frequencies except those side frequencies

between 4200 and 6000 cycles. The filters F¹, F², and F³ thus supply speech bands of normal width but ranging one above the other. These are impressed upon the modulating circuit 2. Another signaling channel 70 may be developed by effectively increasing the speech frequency band by a 6000 cycle frequency giving a side frequency ranging between limits of 6200 and 8000 cycles and so on. Any number of such circuits can be employed wherein the modulations caused by the speech frequencies are superimposed upon local generating circuits of such frequencies as 2000, 4000 and 6000 cycles or 75 more. The precise increase in frequency 80 of any of the signal waves is immaterial so long as the resulting bands impressed on the grid circuit of the balanced modulator 2 do not overlap in frequency. Preferably these resulting bands will be separated by 85 a certain frequency interval to permit good selectivity at the receiving station without recourse to elaborate selecting means.

Having modulated the carrier wave from 90 source 1 at the various modulation frequencies a typical one of which might be represented by S, the output of the tubes of the circuit 2 is then transferred through the split primary winding 10 and 11 to the grid circuit 14 of the power amplifier tubes 20. The phase adjuster 17 and the inductance 16 are 95 adjusted so that an unmodulated carrier frequency component is supplied to the grid circuit 14 which will just neutralize the unmodulated carrier frequency component supplied from the moderator circuit 2 as a result of its repeating action. The output of the power amplifier tubes is then delivered to a band filter F⁴ which preferably is 100 capable of passing frequencies represented as C-S or C+S but which may transmit both C+S and C-S, the frequency S representing any frequency of a current impressed from any signal channel upon the input circuit of the balanced modulator 2. Accordingly in the particular arrangement illustrated C+S typifies a band of frequencies ranging from 100,200 to 106,000 cycles. Since the carrier frequency C is eliminated 105 there is no component of carrier frequency 110 transmitted. The band filter may therefore be capable of passing frequencies (C-S) between 94,000 cycles and 99,800 cycles or (C+S and C-S) 94,000 to 106,000 cycles. The output of this band filter is then delivered to an antenna radiating system 30 or to 115 a line wire system.

The received wave from such a system will 120 contain frequencies covering the entire range transmitted. It is desirable to introduce energy of the original carrier wave frequency by supplying a local source of oscillations which is identical in frequency with the original carrier wave frequency. In Fig. 2 is 125 shown the receiving system wherein energy 130

- is brought into the station by the antenna system 33 or the line wire system. The amplitude of the initial received energy may be increased by any desired number of stages of 5 radio frequency amplification represented by electron tube 36. A wave of carrier frequency is introduced by a suitable generator 35. The amplified received energy and the locally supplied energy of carrier frequency are impressed 10 on the grid circuit of a detector tube 37. The detecting action of this tube 37 is such as to produce in the output circuit of this tube currents which contain frequency components between 200 cycles and 6,000 15 cycles, corresponding to the modulating frequencies supplied to the balanced modulator 2 at the transmitter. The output of the detector circuit is delivered to a band filter FR which filter suppresses any current of the 20 carrier wave frequency that may be in the plate circuit of the detector tube and allows only frequencies between 200 and 6,000 cycles to pass on to the amplifier 39 which is common to all the signaling channels. The output 25 of the amplifier 39 is connected to a number of circuits corresponding to the number of signaling channels at the transmitter. By way of illustration three separate circuits are shown connected to the secondary of the 30 audio frequency transformer 40. In circuit 41 a band filter FR¹ is connected which allows frequencies varying between 200 to 2000 cycles to pass. These currents are of audible frequency, and represent speech. 35 They may be amplified in a vacuum tube amplifier circuit 41 before being impressed upon the receivers 48 to reproduce the speech corresponding to the channel containing the filter F¹ at the transmitting station.
- 40 In the second circuit 42 a band filter FR² allows currents of frequencies between 2200 and 4000 to pass. The currents of this band of frequencies are then passed on to a detector tube 46 which is provided with a local 45 source of oscillations 45. The local source of oscillations in this case is a 2000 cycle generator. The difference in frequency between the incoming signal waves passed by filter FR² and the 2000 cycle oscillator will give 50 rise to a signal in the telephones 48 which will be equal to voice frequency or, in other words, from 200 to 2000 cycles. A filter FA² is used in this circuit between the output of the amplifier tube and the telephone 55 receivers. This filter may be of the band or low pass filter type, preferably of the low pass filter type, wherein frequencies below 2000 cycles are permitted to pass to the telephone receivers while excluding the low frequency note 60 of the local oscillator 45.
- In circuit 43 a band filter FR³ which is capable of passing frequencies between 4200 and 6000 cycles is connected. The output of this band filter FR³ is delivered to the grid 65 of a detector tube 47, the input circuit of
- which is associated with a local source of oscillations of approximately 4000 cycles frequency. The difference in frequencies between the incoming signal waves passed by filter FR³ and the local source of oscillations corresponds to frequencies between 200 and 2000 cycles. This frequency is passed on to the telephone receivers in the same manner as in circuit 42 but utilizing a filter FA³.
- The method of operation of the multiplex system will be understood from the preceding description. It will be observed that the speech signal containing frequencies ranging from 200 to 2000 cycles is effectively increased in all but one of the channels by predetermined fixed frequencies determining the signaling channels each of which independently modulate a single carrier wave without cross modulation and with the carrier frequency eliminated.
- A characteristic feature of the invention is in the application of signal or modulating waves to the modulator circuit 2 in such a manner that the signal waves themselves are suppressed in the modulator as distinguished from the method in which the signal waves are so applied as to be repeated to the output circuit and the carrier wave so applied as to be suppressed. Since the modulator itself does not suppress the carrier wave in the present arrangement the channel 16, 15 and 17 is provided for this purpose.
- At the receiving station, a local source of oscillations of the principal carrier frequency may be used to produce in the output circuit of the first detector, waves corresponding in frequency to the "separate signals" applied to the modulator input. These "separate signals" are selected by band filters and each of these but one is "beaten" with locally produced low frequency oscillations of 2000, 4000 cycles, etc., in a second detector, the output circuit of which is provided with a low pass filter which will eliminate the low frequency beating oscillations and transmit the original speech signals.
- One of the separate signals is of speech frequency and is applied directly to the receiving telephone or low frequency line without the intervention of a local source of oscillations.
- In the present specification a band of frequencies of from 200 to 2000 cycles per second is chosen as illustrative of a band suitable for commercial practice. Wider or narrower bands and higher or lower frequency ranges may be used.
- The band filter FT may be relied upon to suppress any component of unmodulated carrier frequency not suppressed by the channel 15, 16, 17. If it is too difficult or expensive to construct a filter to suppress 100,000 cycles and pass 100,200 cycles the speech frequency channel containing the filter F¹ may be omitted.

While I have illustrated the invention in a particular embodiment, such as employing a circuit for suppressing the carrier wave frequency at the transmitter, it should be understood that modifications may be made, such as eliminating the restoring carrier frequency at the receiver and allowing the carrier frequency to be transmitted, without departing from the spirit of my invention as covered by the appended claims.

What is claimed is:

1. In a signaling system two modulator devices for modulating a carrier wave in accordance with a plurality of separate signaling waves, means for impressing in the same phase the plurality of separate signaling waves on the modulators, means for impressing the carrier wave upon the modulating devices in opposite phase whereby all of the signals are transmitted with a minimum of cross modulation, and additional means for neutralizing the unmodulated component of the carrier wave frequency in the output circuit of said devices.
2. In a signaling system a source of carrier wave energy, a modulator consisting of a pair of oppositely connected electron tubes, a plurality of signaling circuits connected to said tubes to apply voltages thereto in the same phase, and means for suppressing the unmodulated component of carrier wave frequency.
3. In a signaling system a modulator circuit, means for impressing carrier waves and signaling waves on said modulator circuit, means for suppressing the unmodulated carrier frequency component from the output circuit of said modulator, and means for supplying signaling waves to said modulator in such a way that currents of the signaling wave frequency do not appear in the output circuit.
4. A system comprising two space discharge devices having input circuits and output circuits, a plurality of sources of waves each involving a variety of frequencies in a variety of phase relations connected to said

input circuits to apply electromotive forces thereto in the same phase relation, a source of waves essentially of a single frequency connected to similar circuits of said devices to apply electromotive forces thereto in opposite phase relation, an output channel for conducting waves from said devices, and a channel from said last named source of waves connected to said output channel including phase and amplitude controlling means.

5. A modulating system comprising a plurality of sources of signaling waves each representing a signal or message, a space discharge device modulator comprising two devices each having a grid-cathode circuit, connections between said sources and said grid cathode circuits, each said connection being similar to the others, and the potentials impressed on the respective grids from said connections each being equal to the others and having the same phase, a carrier source, and means for impressing waves from said carrier source on said grid-cathode circuits in relatively opposite phase.

6. In a plural channel telephone system, a plurality of sources of speech representing waves, means for translating the frequencies of the waves from each but one of said sources to a high frequency range so that the translated and untranslated speech representing waves are arranged in frequency one above the other, means for modulating a carrier wave in accordance with the resultant speech representing waves and suppressing both the carrier and speech representing waves to produce corresponding speech representing waves of translated frequency range, and a receiving system comprising means for isolating and observing at least one of the speech representing waves independently of the others.

In witness whereof, I hereunto subscribe my name this 27th day of February, A. D. 1923.

RAYMOND A. HEISING.
